UNITED STATES PATENT OFFICE.

CHARLES P. GOULD, OF EAST BRAINTREE, MASSACHUSETTS, ASSIGNOR
TO FORE RIVER SHIP BUILDING COMPANY, OF QUINCY, MASSACHU-
SETTS, A CORPORATION OF MASSACHUSETTS.

VENTILATION-TERMINAL.

No. 829,961.

Specification of Letters Patent.

Patented Sept. 4, 1906.

Application filed April 13, 1905. Serial No. 255,325.

To all whom it may concern:

Be it known that I, CHARLES P. GOULD, a citizen of the United States, residing at East Braintree, in the county of Norfolk and State 5 of Massachusetts, have invented new and useful Improvements in Ventilation-Terminals, of which the following is a specification.

This invention relates to an improved conical sectional pipe in which the sections are 10 adapted to be rotatably adjusted one upon the other, so that by placing said sections in the correct positions to each other said pipe may be formed as a frustum of a cone, or said sections may be so arranged that said pipes 15 will form as a whole a curved structure known as an "elbow" or as a "cowl" in the respective classes to which this invention pertains.

The object of the invention is to provide a device of the character described, the same 20 being particularly adapted to the construction of ventilation terminals or outlets for ventilation-pipes, such as are used on steamers, vessels, and the like, and to this end it is particularly desirable that the outlet-terminal 25 of a ventilation-pipe should gradually increase in diameter from the point of beginning thereof—that is, at the upper end of the ventilation-pipe proper to the outlet-orifice thereof; second, said ventilation-terminal 30 should be capable of adjustment so that it may be placed with the outlet-orifice thereof in a horizontal or vertical position or at any desired angle intermediate between said horizontal and vertical positions; third, said elbow or terminal in all its varied forms and positions should have a symmetrical shape in order to provide for the proper distribution 35 of air at the delivery end thereof, and thus prevent "whistling" under pressure; fourth, 40 the different sections of said terminal must accurately fit each other in the different positions in which they are placed.

It is also the object of this invention to provide a cap for the outlet-orifice of the ventilation-terminal to prevent extraneous articles 45 from entering said terminal, which cap may be easily attached to or detached from the outlet end of said terminal, and, further, it is the object of this invention to provide a 50 damper which, in combination with said ventilation-terminal, regulates the flow of air through the ventilation-pipe and which may be locked in any desired position.

The invention consists of a pipe formed of a plurality of conical sections, the opposite 55 ends of said conical sections lying in converging planes and the adjacent edges of said sections rotatably mounted one upon the other, so that said pipe may be by the relative adjustment of said sections one to the other 60 formed as a frustum of a cone or as an elbow and with its outlet-orifice in a substantially horizontal position or in a vertical position or at any desired angle between a horizontal and a vertical position. 65

The invention further consists in the combination, with a pipe or ventilation-terminal, of a damper adapted to be locked in different positions.

The invention again consists in a ventilation-terminal having a cap detachably fastened to the outlet end thereof in the manner hereinafter set forth, and finally the invention consists in the combination and arrangement of parts set forth in the following specification and particularly pointed out in the claim thereof. 70

Referring to the drawings, Figure 1 is a side elevation, partly broken away and shown in section, of a form of my invention as adapted 80 to ventilation-terminals. Fig. 2 is a front elevation of the same as viewed from the right of Fig. 1, with the damper-lock cap shown in section. Fig. 3 is a side elevation of my improved ventilation-terminal, illustrating the 85 different conical sections in the correct position with relation to each other to form a cone. Fig. 4 is an enlarged section, partly in elevation, taken on line 4 4 of Fig. 1, illustrating the manner of attaching the cap to 90 the ventilation-terminal. Fig. 5 is an enlarged section taken on line 5 5 of Fig. 1. Fig. 6 is an enlarged section taken on line 6 6 of Fig. 3. Fig. 7 is a section taken on line 7 7 of Fig. 5. 95

Like numerals refer to like parts throughout the several views of the drawings.

In the drawings, 10 is the ventilation-terminal as a whole, the same consisting of a plurality of conical sections 11, 12, 13, 14, 15, 100 and 16. The opposite ends of said conical sections or cone-frustums lie in two converging planes, and each of said conical frustums is rotatably connected to the frustums adjacent thereto, the edges being formed in hemispherical shape to fit one upon the other, as 105

illustrated in Fig. 6, in which the edge 17 of the section 12 is formed in hemispherical shape to encircle the edge 18 of the section 13, so that the edges of each of said frustums 5 form a closely-fitting joint with the edge of the cone-frustum adjacent thereto, and each of said cone-frustums may be rotated upon the adjacent cone-frustum.

The section 16 is provided with a rim 19, 10 securely fastened thereto by soldering, and to said rim are fastened two radial pins 20 upon diametrically opposite sides of said rim. The cap 21 consists of a ring 22, with a screen 23 extending thereacross and fastened thereto. The ring 22 is provided with an annular recess 24, into which the rim 19 fits. Said ring is also provided with two annular grooves 25, which extend partly therearound and into which the outer ends of the pins 20 project when the cap is in position upon the outer end of the terminal section 16 and locked thereto, as hereinafter described. Slots 26 open outwardly from the annular grooves 25 in the ring 22, said grooves extending beyond said slots upon opposite sides thereof, respectively.

In order to attach the cap 21 to the terminal 10, the same is placed in the position illustrated in Fig. 2, with the pins 20 in alinement 15 with the lateral slots 26, formed in the ring 22, and said cap 21 is then pushed onto the rim 19 or toward the left, Fig. 1, and into the position illustrated in Fig. 1. Said cap is then rotated toward the right or left and the pins 20 thus pass into the annular grooves 25, and thus the cap is locked to the rim 19 and to the section 16. By reversing the rotation hereinbefore described of the cap 21 until the pins 20 come in line again with the lateral 20 slots 26 said cap may be removed by drawing the same off of the rim 19 or toward the right, Fig. 1. It will be seen and understood that by continuing the grooves 25 circumferentially beyond the slots 26 upon opposite sides thereof the accidental disconnection of the ring 22 from the rim 19 is prevented. This accidental disconnection would be very liable to occur if the groove 25 terminated at one end thereof in line with the slots 26, for 25 the reason that in changing the relative location of the different conical frustums to each other the ring 22 is grasped by the operator and rotated, turning the conical frustums in the direction desired to change the angle of the ventilation-terminal as a whole. Now if the groove 25 terminates in alinement with the lateral slots 26 it is evident that when the ring is rotated, as hereinbefore described, unless the operator remembers to take the 30 precaution of rotating the ring in the opposite direction when he has finished adjusting the conical frustums the pins 20 will be left in alinement with the slots 26 and therefore the ring 22 will be in position to be accidentally

jarred off the end or the terminal or off of the 65 rim 19. By extending the groove 25 circumferentially beyond opposite sides of the slots 26, respectively, this accidental jarring of the ring from its place is prevented.

A cylindrical band 27 is fastened to the 70 section 11, said band constituting the upper end of the ventilation-pipe proper, and a damper 28 of the form known as a "butterfly-damper," is rotatably supported in said cylindrical band, the object of said damper 75 being to regulate the flow of air through the ventilation-pipe and through the terminal. Said damper consists of a disk 29, provided with two studs 30 and 31, fastened thereto at diametrically opposite sides thereof. The 80 stud 31 is provided with a handle 32, by means of which it may be rotated. The stud 30 is journaled to rotate in the band 27, the stud 31 being journaled to rotate in a bearing-sleeve 33, fast to the band 27 and provided 85 with V-shaped teeth 34 upon the outer end thereof, which mesh into similar teeth 35, formed upon the left-hand face, Fig. 2, of a washer 36. The washer 36 has a square hole 37 formed therein, and through this hole 90 projects a rectangular portion 38, formed upon the stud 31. The washer 36, it will be understood, rotates with the stud 31 and handle 32 and is slidable longitudinally thereof upon the rectangular portion 38 of said stud, 95 the teeth of said washer and bearing-sleeve being held in contact or in mesh with each other by a spiral spring 39, one end of which bears against said washer and the other against the end of a cap 40, which surrounds 100 the spring 39 and washer 36 and has screw-threaded engagement with the bearing-sleeve 33.

While I have described my invention as particularly applicable to the terminal of a 105 ventilating-pipe, it is evident that the same may be used in connection with other kinds of pipes in which a conical end is desired and in which said conical end may be changed in form from a straight conical frustum to an 110 elbow, gradually increasing in diameter from one end to the other thereof.

The damper illustrated and described in the foregoing specification is made the subject-matter of a separate application, Se- 115 rial No. 225,326, filed April 13, 1905.

The operation of my invention hereinbefore specifically described is as follows: Assuming the terminal to be in the position illustrated in Fig. 1, in which the different conical frustum-sections are arranged relatively to each other in such a position as to form an elbow, with the outlet-orifice of said elbow in a substantially vertical plane, and that it is desired to change said terminal to the form illustrated in Fig. 3, in which said terminal consists of a cone, with the outlet end thereof substantially horizontal, each alternate sec-

tion is given a half-rotation upon the section adjacent thereto. For instance, the sections 12, 14, and 16 are given a half-rotation upon the sections 11, 13, and 15, respectively, thus 5 changing the form of the terminal from an elbow (shown in Fig. 1) to a frustum of a cone. (Illustrated in Fig. 3.) The damper is operated by turning the handle 32 until the disk 29 stands at the angle desired to allow the 10 proper amount of air to pass through the terminal, and during such movement of the handle the washer 36 rotates therewith, the teeth 35 on the washer springing out of the teeth 34 on the sleeve to allow said rotation 15 and being forced back into mesh with each other when the proper position of the disk 29 is finally obtained by the spring 39, thus locking the damper in the desired position against accidental displacement. The manner 20 of attaching and detaching the cap 21 to

and from, respectively, the rim 19 has been hereinbefore fully described.

Having thus described my invention, what I claim, and desire by Letters Patent to secure, is—

An adjustable ventilation-terminal constructed of a plurality of frustums of a cone, said frustums having inclined opposite ends and straight sides rotatably connected together about their longitudinal median axes 30 and forming, as a whole, a terminal increasing in diameter throughout its length from one end to the other thereof.

In testimony whereof I have hereunto set my hand in presence of two subscribing witnesses.

CHARLES P. GOULD.
